CLAIM

The ornamental design for a vehicle antenna, as shown and described.

DESCRIPTION

This application is related to U.S. patent application Ser. No. 29/655,062, entitled "Vehicle," filed Jun. 29, 2018, the entire contents of which are incorporated herein by reference.

FIG. 1 is a front perspective view of a vehicle antenna;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof; and,

FIG. 8 is an alternative perspective view including disclaimed environment of the vehicle antenna.

The broken lines depict portions of the vehicle antenna or environment of the vehicle antenna which form no part of the claimed design.
